SHEET MOVING MECHANISM FOR SHEET FEEDERS

George Goebel and Sherman A. Chantland, Baltimore, Md., assignors to Crown Cork & Seal Company, Inc., Baltimore, Md., a corporation of New York

Application May 8, 1936, Serial No. 78,706

24 Claims. (Cl. 271—26)

The present invention relates to sheet moving mechanisms for sheet feeders, being an improvement upon the corresponding structure shown in our application for Sheet feeder, Serial No. 25,908, filed June 10, 1935.

The principal object of the invention is to provide a sheet moving mechanism of such design that individual sheets of paper, metal, or the like handled by the sheet feeder will be properly separated from a stack of sheets and forwarded through the feeder to a press or other apparatus for performing an operation thereon.

Another object of the invention, ancillary to the above, is to provide a sheet separator or rear cup operating mechanism which will efficiently separate sheets from the sheet stack and simultaneously cause the sheets to be properly positioned with respect to the forwarder mechanism or front cups.

In the handling of a stack of sheets, in order to separate the uppermost sheet from the next lowest sheet, it is desirable to bend the rear portion of the uppermost sheet upwardly, and suction cups are ordinarily used for this purpose.

By the action of the separators used in most types of sheet feeders, the rear portion of the sheet is bent upwardly along a line extending crosswise of the sheet. In handling some materials, particularly thin sheets of metal, when the rear suction cups act to bend the sheet on a line extending transversely thereof, the sheet frequently has a tendency to buckle along a line at right angles to its rear edge, resisting the efforts of the suction cups to bend its rear portion.

The separator mechanism of the present invention is designed to bend the rear corners of the top sheet upwardly on a diagonal bending line, instead of bending the entire rear portion on a transverse line. Obviously, the corners can be bent much more readily than the entire rear portion, since the buckling tendency of the sheet referred to above will not be encountered.

Separator mechanisms of the type now customarily used are also objectionable, for the reason that in bending the rear portion of a sheet upwardly, whether bending the entire rear portion or merely the rear corners, the suction cups tend to move the sheet rearwardly and away from the stack gauge plate and forwarders.

The tendency of the suction cups or separator mechanism to move sheets backwardly during the bending or separating movement results from the fact that the sheet engaging element or cup must be pivoted to its support at a point spaced above the uppermost sheet of the stack. When the suc-

tion cups swing upwardly on this pivot point, the sheet is dragged upwardly and backwardly, (in effect, around the pivot point) and is thereby moved away from the stack gauge plate. Such movement of the top sheet will be transmitted to a number of sheets immediately below, until the upper portion of the stack may, by continued backward dragging action, be positioned so far backwardly from the stack gauge plate that the front suction cups or forwarder mechanism will not be able to contact with the front portion of the uppermost sheet, thereby temporarily stopping feeding of the sheets through the machine. Also, since the backward dragging of uppermost sheets may not be transmitted equally over the entire area of the sheets, the entire upper portion of the stack may become slightly twisted, so that the front edges of the sheets will be fed through the machine on an angle.

The construction of the separator mechanism of the present invention is such that the suction cup or sheet engaging element will have what may be best generally described as a forward movement with respect to the remainder of the elements of the separator mechanism, the engaging element having a definite tendency to move inwardly or forwardly with respect to its pivot point as it moves upwardly to bend the sheet. This arrangement entirely prevents the sheet from being dragged backwardly; in fact, a definite force will be applied to the sheet to hold it forwardly against the stack gauge plate.

Another object of the invention is to provide a separator mechanism which is readily adjustable to operate upon sheets of various dimensions.

The construction of the separator mechanism of the present invention is such that the sheet engaging elements will be longitudinally and also laterally adjustable, a minimum number of adjusting operations being necessary to attain the desired range of position.

Another object of the invention is to provide a forwarder mechanism which will be positive in action toward moving a sheet from the stack when the rear corners of the sheet are released from the suction of the rear suction cups or separators, and which forwarder mechanism is of such design that there will be minimum wear upon its moving parts.

The forwarder mechanism of a sheet feeder must lift the uppermost sheet from the stack and then carry it forward to position it upon the feed table, the most efficient movement for this purpose being an initial upward movement to lift the sheet, and a relatively long horizontal move-

ment to carry the sheet to a point above the feed table where it may be released. It is necessary that on the reverse movement, that is, the movement during which the forwarder is moving toward the stack to engage a sheet, it should be moved by a means having some degree of resiliency, because the height of the top of the stack may vary and if the forwarder were positively moved down upon the stack when the latter is higher than usual, breakage of the forwarder might result.

To meet the requirements set forth above, fairly complicated cam and trip mechanisms have been used to operate the forwarder, but the most efficient form of operating mechanism may be generally described as comprising a cam to positively move the forwarder and lift sheet away from the stack, and a spring to move the forwarder toward the stack. However, with such an arrangement, the cam, in its positive driving action, has heretofore operated against a relatively strong spring, thereby increasing the load upon the driving motor of the machine, and also resulting in heavy wear upon the moving elements of the forwarder.

The construction of forwarder mechanism provided by the present invention is such that only a relatively light spring need be provided to obtain the resilient drive desirable when the forwarder is approaching the stack, the cam following device which is provided to transmit the movement of the cam to the forwarder being of such form that it will, in effect, embrace the cam at all times, but with the elements of the embracing or following mechanism being resiliently connected.

Other objects and advantages of the invention will be apparent from the following drawings wherein:

40 Figure 1 is a longitudinal vertical sectional view through a sheet feeder showing the sheet moving mechanisms of our invention; the central portion of the view being taken on the line A—A of Figure 2;

45 Figure 2 is a horizontal sectional view showing the rear cup mechanisms in top plan view, the front cup mechanisms being omitted from this view;

Figure 3 is a vertical sectional view taken on the line 3—3 of Figure 2;

Figure 4 is a fragmentary vertical sectional view similar to Figure 3 and showing a rear cup in raised position;

Figure 5 is a vertical sectional view taken on the line 5—5 of Figure 3;

Figure 6 is a vertical sectional view taken on the line 6—6 of Figure 3;

Figure 7 is a vertical sectional view showing the forwarder mechanism;

60 Figure 8 is a horizontal sectional view taken on the line 8—8 of Figure 7;

Figure 9 is a horizontal sectional view taken on the line 9—9 of Figure 7;

Figure 10 is a horizontal sectional view taken on the line 10—10 of Figure 7; and

Figure 11 is a vertical sectional view taken on the line 11—11 of Figure 7.

Referring to the drawings, the numeral 85 designates a longitudinal beam included in the upper portion of the frame of a sheet feeder of the type shown in our application for Sheet feeder, Serial No. 25,908, filed June 10, 1935. The numeral 56 designates the main cam shaft of the machine, which is rotated by a driving mechanism fully described in the above mentioned ap-

plication, and which driving mechanism forms no part of the present invention. The cam shaft 56 has fixed thereto a cam 601 for controlling the movement of the forwarder mechanism 602 of the present invention and, through gearing best shown in Figure 2, operates a cam 603 which controls the movement of the sheet separator mechanism generally indicated by the numeral 604.

As best shown in Figure 2, the sheet separator mechanism comprises two separator elements 605, 10 each supported from a casing 114 which, at its forward end (the right-hand end in Figures 1, 2 and 3), is journaled for upward swinging movement upon the cam shaft 56. A vertical plate 115 extending downwardly from a cross bar 88 15 forming part of the frame of the feeder is provided at its lower end with a shelf or hook 115a upon which a shoulder 114a on the rear face of the casing 114 normally rests. The main cam shaft 56 has a beveled gear 116 fixed thereto within the casing 114, which gear meshes with a beveled gear 117 fixed to the end of a shaft 118 extending longitudinally of the casing 114, shaft 118 being mounted in bearings provided intermediate the length of casing 114.

25 The separator operating cam 603 is dish-shaped and is secured to the rear end of the shaft 118, the effective cam surface of the cam being its periphery 606. Cam 603 is arranged to engage rollers 607 mounted on the lower ends of levers 608 journaled on pins 609 fixed in each side wall of the casing 114, with the result that the levers 608 will be swung by rotation of the cam. The upper ends of the levers 608 extend through the upper wall of the casing 114 and each lever has a 30 rod 610 pivotally connected thereto by a universal joint connection 611 comprising a vertically swinging knuckle 612 pivotally connected to the upper end of the lever and pivoted to a horizontally swinging knuckle 613 forming part of the 40 rod 610. The opposite or rearward end of each rod 610 is pivotally connected as at 614 to the outer and upper member 615 of a two-piece suction cup supporting device 616, the other member 617 of each element 616 being pivotally connected as at 618 to a bracket 619 carried by a hanger 620 supported on the casing 114 by means of a pivot pin 621 upon which the hanger is enabled to swing for adjustment in a horizontal plane in a manner hereinafter described.

45 As is best shown in Figure 3, the inner member 617 of each suction cup supporting device 616 has a flat upper surface 622 and the inner portion of the outer member 615 is provided with a flat lower surface 623, which surface may bear upon the surface 622 when the suction cup is in its lowermost position shown in solid lines in Figure 3. The upper member 615 is joined to the lower member 617 by pairs of parallel links 624, with the result that the upper member 615 50 may move to the right, upon lifting movement of the link 610, from the position shown in solid lines in Figure 3 to the position shown in dotted lines in that figure and also shown in solid lines in Figure 4. The movement of member 615 with respect to member 617 will be accomplished by a swinging or translational movement upon the links 624. Such movement of the upper member 615 with respect to the member 617 will be resisted to some extent by an expansion spring 55 625 positioned between the rear or left-hand end of the inner and lower member 617 and a vertical face 626 on the outer and upper member 615, the spring being centered and held in position upon projection 627.

Each outer and upper member 615 has a suction cup 132 mounted thereon, which suction cup is connected by a flexible tube 135 with a suction pump, not shown.

5 The suction cups 132 are arranged to be adjustable over a wide area in order to permit the mechanism to operate upon sheets of various sizes. This adjustability is attained by reason of the fact that, as shown in Figure 3, the connecting rod 610 is telescopic, the outer or sleeve element of the rod being split at its free end and provided with a set screw 630 to permit the two sections of the rod to be held in adjusted position. The bracket 619 which supports each suction cup supporting device 616 with respect to its hanger 620 is provided with a pair of vertically spaced rods 632 slidable in sleeves 633 mounted in semi-cylindrical grooves 634 and 635 respectively provided in the hanger 620 and a clamping member 636. The rods 632 are provided with heads 637 at their outer ends which are adapted to contact with shoulders 638 formed in the interior of the tubes 633 when the bracket 619 is drawn outwardly for adjustment as shown in Figure 1. Further outward movement of the brackets will cause the tubes 633 to slide with respect to the hanger 620 and clamping member 636, this movement being limited by shoulders on the outer ends of the tubes and indicated by the numeral 639. The brackets 619 will be held in the desired adjusted position with respect to the hangers 620 by means of a bolt member 640 threaded in a nut 641 (Figure 5) carried in the outer face of clamping member 636, the bolt 640 extending through hanger 620 and being provided with a large knurled thumb wheel 642.

In order to permit the hangers 620 to be swung on their pivots 621 by a simultaneous action, links 644 are pivoted to the inner faces of the hangers. the adjacent ends of the links being respectively arranged above and below and in overlapping position with respect to a rearward extension 645 of the housing 114 and in alignment with a slot 646 in the extension. A bolt and nut indicated by the numeral 647 and best shown in Figure 1 is provided in the slot 646 and extends through the links 644 to hold the latter in adjusted position with respect to the extension. Washers 648 having squared faces to fit the slot are provided between each surface of the slot and the corresponding link to guide the bolt in the slot. By this arrangement, when the bolt and nut are unthreaded with respect to each other and the bolt is slid in the slot 646, the hangers 620 carrying the suction cups will be simultaneously swung upon their pivots 621, thereby varying the angle of the elements of the separator mechanism with respect to each other.

60 The operation of the separator mechanism is as follows:—

When the cam 603 rotates to present its low portions to the rollers 607 of the levers 608, these levers will move to the position shown in solid lines in Figure 3, permitting the suction cups 132 to drop upon the top sheet of the stack. Immediately thereafter, suction will be exerted within the suction cups 132 so that when the high portions of the cam 603 come in contact with the rollers 607 to lift the suction cups, the rear corners of the sheet will be bent upwardly in the manner shown in Figures 1 and 4 and in dotted lines in Figure 3.

70 The pull exerted through the rod 610 upon the upper member 615 of the cup supporting

element 616 will tend to both lift the member 615, and thereby the member 617, and will also tend to swing the member 615 upwardly and forwardly (to the right) upon the links 624 with respect to the member 617. The effect of this 5 swinging or translational movement of the member 615 with respect to the member 617 is best illustrated by a comparison of the line A of Figure 4 with respect to the line B. That is to say, the line A indicates the path of travel which would 10 be followed on its lifting movement by the center line of the suction cup 132 if this cup were carried by a rigid element pivoted to the bracket 619 at the pivot point 618, this line of movement corresponding to an arc drawn upwardly 15 from the point a on a radius a' centered at the axis of pivot 618. Since the pivot point 618 is spaced above the uppermost sheets of the stack, it naturally follows that if a cup moves upwardly along the line A, it moves outwardly 20 from the stack gauge plate 61 (Figure 1), resulting in the sheets being moved rearwardly and away from the stack gauge plate and the fingers 62 forming the upper portion of this plate. The line A' followed by the rear edge of a sheet 25 lifted in such manner clearly indicates the rearward movement. As has heretofore been set forth in detail, any action tending to drag the uppermost sheet rearwardly away from the stack gauge plate 61 causes the next lowest sheets to 30 be tended in the same direction and such action, repeated upon successive uppermost sheets, tends to cause all of the sheets of the upper portion of the stack to be moved rearwardly to an increasing extent until it is possible that the uppermost 35 sheet may be positioned rearwardly of the suction cups of the forwarder mechanism 602. Another common difficulty resulting from the tendency of the separator to move the sheets rearwardly is that the sheets may be turned upon the 40 stack in the manner indicated by the dotted line C of Figure 2, due to the fact that the backward dragging motion may not be equally transmitted between the sheets. If the sheets are in a turned or canted position when engaged by the forwarder, they will not be properly positioned while 45 passing through the remaining mechanisms of the feeder, for example, the caliper mechanism, and difficulties may thereby result.

The line B of Figure 4 indicates the path of movement of the center line of a suction cup 132 50 when the latter is raised by the supporting element 616 of the present invention. From this line, it will be noted that the cup moves upwardly in a substantially straight line because member 615 moves inwardly and upwardly over member 617 as element 616 moves upwardly, thereby entirely avoiding any rearward movement of the sheet. In actual practice, it is found that the translational or contractile connection between 55 the members 615 and 617 tends to move the sheets forwardly and toward the stack gauge plate 61, at the highest point of lifting movement of the suction cup, indicated in solid lines in Figure 4, 60 thereby holding the front edge in proper position with respect to the forwarder mechanism and preventing turning of the uppermost sheets with respect to the stack.

The forwarder mechanism

70 Two of the forwarders 602 are ordinarily provided upon a feeder, one adjacent each side of the stack 51. Since the construction of the two forwarders is identical, the following description 75

of the detailed construction of one will apply to both.

Each forwarder is supported from a transverse beam 86 of the machine, as shown in Figures 1 and 7, the supporting frame 150 of the forwarder being rigid with the beam. The supporting frame 150 is in the form of a bar or beam extending in a direction lengthwise of the machine and having its ends curved downwardly as indicated at 151. The ends of rods 152 are supported in bores provided in the downwardly extending ends 151 of the bars 150, the rods 152 being horizontally spaced as shown in Figures 10 and 11 to form a track-way. A plate 153 is bolted to each side of the bar 150 adjacent the rear end thereof (the left hand end as viewed in Figures 1, 7 and 10), these two plates being curved outwardly from the bar 150 as shown in Figure 11 and thence extending downwardly past the rods 152. The lower ends of the plates 153 are angled toward each other and each plate has fixed thereto an upwardly facing cam track best shown in Figures 1 and 7. A plate 155 is fixed to each side of the bar or beam 150 adjacent its forward end (right-hand end in Figures 1, 7 and 10), these plates extending downwardly to a point somewhat below the rear plates 153 and serving to support between them a pin 156 for a purpose hereinafter set forth.

A forwarder carriage 157 is slideable upon the trackway formed by the rods 152, the carriage having bores extending therethrough to embrace the rods. From the forward end of the carriage 157, the right hand end of Figures 1, 7 and 10, there extends a link 158 which is pivotally connected to the upper portion of the carriage 157 by means of a pin 159 journaled in the carriage. The link 158 preferably includes a turn-buckle device, as shown, to permit its length and thereby the movement of the carriage 157 to be adjusted. The forward end of the link, at the right-hand end in the drawings, is pivotally connected to a lever 652 mounted to swing on the pin 156 extending between the lower ends of the front plates 155. At a point adjacent its lower end, the lever 652 carries a roller 653 arranged opposite the cam 601 on the main cam shaft 56.

The plates 155 are each provided with integral rearward extensions 654 which have a pin 655 extending between them at their rearward ends and to the rear and below the main cam shaft 56. A lever 656 is mounted on the pivot pin 655 between the extensions 654, the lever being provided with a roller 657 adapted to contact with the cam 601, and the upper end of lever 656 being pivotally connected, as at 658 to a horizontally extending yoke or connecting member 659 which extends about and forwardly past the lever 652. A pin 660 extends through the two bars forming the lever 652 and into a horizontally extending slot 651 formed in each arm of the yoke 659. A headed guide member or rod 652 has its head 663 fixed to the pin 660, the end of the guide member 662 extending through an aperture in the bight 664 of the yoke 659. An expansion spring 665 encircles the guide member 662, one end of the spring bearing on the inner side of the bight 664 and the opposite end bearing on the head 663 of the guide member 662. By this arrangement, the spring 665, because of its bearing on the lever 652, tends to pull the yoke 659 forwardly or to the right, with the result that the roller 657 will be held in contact with the cam 601 and the lever 656 will be held sub-

stantially parallel to the lever 652, providing a cam following frame about the cam 601, which following frame has some degree of resiliency with respect to the cam by reason of the spring connection between levers 652 and 656.

A suction cup or sheet engaging element 172 fixed to the lower end of a rod 173 is supported upon links 174 and 175 pivotally connected to the rear end of the carriage 157. Link 175 is pivoted on a pin extending between trunnions 10 176 on the extreme upper portion of the rear end of the carriage and is pivotally connected to the upper end of the cup carrying rod 173. Two links 174 are pivotally connected to the lower rear portion of the carriage, one on either side 15 thereof and both extending inwardly to be pivotally connected to the cup supporting rod 173 intermediate the length of the latter. The links 174 and link 175 are of equal length and the distances between the axes of their pivots 20 upon both the carriage and the cup supporting rod 173 are the same, with the result that the links will always be parallel. The lower links 174 have rollers 177 journaled on their outer sides and these rollers are adapted to move along 25 the members of cam track 154 when the carriage 110 reciprocates. As shown in Figure 7, the rear end of each of the members forming cam track 154 is cut away to form a low portion 178, which low portion has an incline 179 extending upwardly therefrom to the high portion 180 of the track, the high portion 180 being of substantial length. The suction cup 172 is connected by tubing 184 with a suitable valve mechanism whereby the suction within the cup may 30 be controlled. As is described in our sheet feeder application hereinbefore referred to, the valve mechanism is so operated that suction will be exerted by the cup 172 when it contacts with the surface of the uppermost sheets of the stack, 40 this suction becoming effective immediately prior to the release of the suction in the suction cups of separator mechanism 604.

The operation of each forwarder mechanism 602 is as follows:—

As the high portion 601a of cam 601 on main cam shaft 56 moves in a counter-clockwise direction from the position shown in Figure 7 to that shown in Figure 1, the lever 652 and carriage 157 will be moved to the left until the Figure 1 position is reached. This movement of the lever 652 and carriage 157 will be accomplished by reason of the fact that as the high portion 601a of the cam moves from beneath the roller 653 on lever 652, it will move beneath the roller 657 on the lever 656, forcing the latter lever to swing to the left and thereby exerting a pull, through spring 665, upon the lever 652, the spring providing a certain degree of resiliency between the cam and the carriage so that should the rearward motion of 60 the carriage be impeded, the result will merely be a further compression of the spring 665.

During the initial portion of the movement of the carriage 157 referred to above, the suction cup 172 will move at the height shown in solid lines in Figure 7 because of the fact that the rollers 177 will then be in contact with the straight and high portion 180 of cam track 154. However, when the rollers 177 reach the inclined portion 179 of the cam track, the cup carrying rod 173 will drop vertically and in a straight line until the roller reaches the low portion 178 of the track. Should the top of the stack be at such a level that the cup cannot move to the lowest position permitted by the cam track, the spring 665 will 70 75

take up the movement which would otherwise be imparted to the cup rod 173 and the carriage 157 by the cam 601.

When the suction cup 172 of a forwarder contacts with the upper sheet of the stack, the valve mechanism of the sheet feeder will cause suction to be exerted within the cup and immediately thereafter will cause the interior of the separator suction cups 132 to be placed in communication with the atmosphere so that the rear corners of the upper sheet will be released from the latter cups. The continuing rotation of the forwarder cam 601 in a counter-clockwise direction will cause the high portion 601a of the cam to move away from the roller 657 on lever 656 and to move beneath the roller 653 on lever 652, causing lever 652 to move from the position illustrated in Figure 1 to the position shown in solid lines in Figure 7. Lever 652 will of course be swung to the right during this movement and lever 656 will be drawn to the right because of the pull exerted by lever 652 on yoke 659 through spring 665.

The above described movement of lever 652 to the right will cause the carriage 157 of each forwarder to be moved from the dotted line position shown in Figure 7 to the solid line position and during the initial portion of this movement, rollers 177 will move upwardly on the inclined portion of cam track 154, the horizontal movement 30 of the carriage and the upward movement of the links 174 and 175 causing the suction cup 172 to move upwardly in a straight line. When the rollers 177 reach the straight portion 180 of the cam track 154, the cup will move in a horizontal direction to position the sheet between the feed rollers 64 and 66 of the feed table 65, the suction in the feed cups 172 being released by the valve mechanism when the sheet has been positioned between the sheet rollers.

It will be obvious that the sheet handling mechanisms described above may be used with sheet feeders other than that disclosed in our above-mentioned application, Serial No. 25,908.

It will be understood that the invention is not limited to the details of construction shown in the drawings and that the example of the use of the mechanism which has been given does not include all of the uses of which it is capable and that the phraseology employed in the specification is for the purpose of description and not of limitation.

We claim:—

1. The combination in a sheet feeder, of a stack gauge plate, sheet separator means, sheet forwarder means, means to operate said separator means to move the rear edge of a sheet away from the stack and urge the sheet against said gauge plate and toward said forwarder means, and means to operate said forwarder means to move the separated sheet past said gauge plate.

2. The combination in a sheet feeder including a frame, of a stack gauge plate, sheet separator means, sheet forwarder means, said separator means being connected to the frame for pivotal and translational movement with respect thereto, to urge sheets toward said gauge plate and forwarder means during sheet separating movement, and means to operate said forwarder means to move a sheet past said gauge plate.

3. The combination in a sheet feeder, of a stack gauge plate, sheet separator means, sheet forwarder means, a support for said separator means positioned above the stack within the bounding edges of the same, means to operate said separator means to move the rear edge of a sheet

away from the stack and urge the sheet against said gauge plate and toward said forwarder means, and means to operate said forwarder means to move the separated sheet past said gauge plate.

4. The combination in a sheet feeder including a frame, of a stack gauge plate, sheet separator means, sheet forwarder means, a support for said separator means positioned above the stack within the bounding edges of the same, said separator means being connected to said support for pivotal and translational movement with respect thereto, to urge sheets toward said gauge plate and forwarder means during sheet separating movement, and means to operate said forwarder means to move a sheet past said gauge plate.

5. A sheet separator mechanism for a sheet feeder including sheet stack supporting means, comprising a support mounted on the body of the feeder above the stack and within the bounding edges of the same, sheet separating elements extending from said support diagonally toward the rear corners of the sheet stack, and means to move said elements upwardly to lift the rear corners of the uppermost sheet of the stack and bend such corners on diagonal lines.

6. The combination in a sheet feeder including sheet stack supporting means, of a support positioned above the stack and within the bounding edges of the same, a sheet separator mounted on said support and arranged to move toward and engage and lift a portion of a sheet on the sheet stack to lift the same, and means to positively engage and lift said separator and the sheet engaged thereby and to release said separator so that it may move down upon a sheet by gravity.

7. The combination in a sheet feeder including a sheet stack, of a supporting element positioned above the stack and within the bounding edges of the same, sheet engaging and bending means, said means being pivotally and bodily movable with respect to said supporting element, and means to move said sheet engaging means with respect to the stack.

8. The combination in a sheet feeder including a frame, of sheet engaging means, an element pivotally connecting said sheet engaging means to said frame, said element being formed of two members arranged for longitudinal and contractile movement with respect to each other.

9. The combination in a sheet feeder including a frame, of sheet engaging means, an element pivotally connecting said sheet engaging means to said frame, said element being formed of two members arranged for longitudinal and contractile movement with respect to each other, and means tending to hold said members in non-contracted position.

10. The combination in a sheet feeder including a frame, of sheet engaging means, an element pivotally connecting said sheet engaging means to said frame, said element being formed of two members, one arranged for inward movement longitudinally along the other.

11. The combination in a sheet feeder including a frame, of sheet engaging means, an element pivotally connecting said sheet engaging means to said frame, said element being formed of two members, one arranged for inward movement longitudinally along the other, and means tending to hold said members apart.

12. The combination in a sheet feeder, of sheet separating means, comprising a frame, a member pivotally connected to said frame, a sheet engaging element connected to said member for

- translational movement with respect thereto, and actuating means operatively connected to said sheet engaging element to move the latter with respect to said member and move said member with respect to said frame.
- 5 13. The combination in a sheet feeder, of sheet separating means comprising a frame, a member pivotally connected to said frame, a sheet engaging element connected to said member for pivotal and body movement with respect thereto, and actuating means operatively connected to said sheet engaging element to move the latter with respect to said member and move said member with respect to said frame.
- 10 14. A sheet separator mechanism for a sheet feeder, comprising a separator supporting element mounted on the body of the feeder, a sheet engaging member, and a telescopic adjustable connection between said member and the frame, the elements of said connection normally being rigid with respect to each other.
- 15 15. A sheet separator mechanism for a sheet feeder, comprising a separator supporting element mounted on the body of the feeder, a sheet engaging member, operating means for said engaging member, and an adjustably extensible connection between said member and said operating means, the elements of said connection normally being rigid with respect to each other.
- 20 16. A sheet separator mechanism for a sheet feeder, comprising a separator supporting element mounted on the body of the feeder, a sheet engaging member, operating means for said engaging member, and an adjustably extensible connection between said member and said operating means, the elements of said connection normally being rigid with respect to each other.
- 25 17. A sheet separator mechanism for a sheet feeder including sheet stack supporting means, comprising a separator supporting element, a pair of sheet engaging members each extending from said frame toward the diagonal corners of the sheet stack, said members being pivotally connected to said supporting element for horizontal swinging movement, and means to simultaneously move said members with respect to said supporting element.
- 30 18. A sheet separator mechanism for a sheet feeder including sheet stack supporting means, comprising a separator supporting element, telescopic sheet engaging members extending diagonally from said supporting element and pivotally connected to the latter to swing in a horizontal plane, said sheet engaging members being pivoted within their length for vertical swinging movement, operating means, a telescopic connection between said operating means and said engaging members, and means to simultaneously swing said engaging members in a horizontal plane.
- 35 19. The combination in a sheet feeder, of a forwarder mechanism to engage and remove sheets from the sheet stack of the feeder, comprising a trackway and a cam track fixed to the frame of the feeder, a carriage movable on said trackway, a sheet engaging member, a pair of parallel and vertically spaced links pivotally connecting said carriage and said member, means
- 40 on one of said links to engage said cam track to cause said member to be moved vertically when said carriage is moved horizontally, and means to move said carriage.
- 45 20. The combination in a sheet feeder, of a forwarder mechanism to engage and remove sheets from the sheet stack of the feeder, comprising a trackway fixed to the frame of the feeder, a carriage movable on said trackway, a sheet engaging member operatively connected to said carriage, means to reciprocate said carriage on said trackway and with respect to the stack for sheet engaging and sheet removing movements, said means including a resilient connection operative on sheet engaging movement of the carriage.
- 50 21. The combination in a sheet feeder, of a forwarder mechanism to engage and remove sheets from the sheet stack of the feeder, comprising a trackway fixed to the frame of the feeder, a carriage movable on said trackway, a sheet engaging member operatively connected to said carriage, an operating cam, a lever pivotally connected between the frame of the feeder and said carriage and actuated by said cam to reciprocate said carriage for sheet engaging and sheet removing movements, said lever being resiliently connected to said cam on its sheet engaging drive movement.
- 55 22. The combination in a sheet feeder, of a forwarder mechanism to engage and remove sheets from the sheet stack of the feeder, comprising a trackway fixed to the frame of the feeder, a carriage movable on said trackway, a sheet engaging member operatively connected to said carriage, a lever pivotally connected between the frame of the feeder and said carriage, a second lever connected to the frame and having a resilient connection with said first lever, an operating cam between said levers and having contact with both to move them simultaneously to thereby control the movements of said carriage.
- 60 23. The combination in a sheet feeder, of a stack gauge plate, sheet separator means, a support for said separator means, said separator means being connected to said support for pivotal movement with respect thereto to have inward bodily movement with respect to said stack gauge plate, and means to operate said separator means to swing the same with respect to said support and to move it bodily toward said gauge plate so as to urge a sheet engaged by said separator means toward said gauge plate.
- 65 24. The combination in a sheet feeder, of a stack gauge plate, sheet separator means, sheet forwarder means, a support for said separator means, said separator means being connected to said support for pivotal movement with respect thereto and to have inward bodily movement with respect to said stack gauge plate, means to operate said separator means to swing the same with respect to said support and to move it bodily toward said gauge plate so as to urge a sheet engaged by said separator means toward said gauge plate, and means to operate said forwarder means to move the separated sheet past said gauge plate.

GEORGE GOEBEL.
SHERMAN A. CHANTLAND.
